(57) **CLAIM**

The ornamental design for a coffee measuring apparatus, as shown and described.

DESCRIPTION

FIG. 1 is a perspective view of a coffee measuring apparatus showing one embodiment of the present invention;

FIG. 2 is a front view thereof;

FIG. 3 is a rear view thereof;

FIG. 4 is a right-side view thereof;

FIG. 5 is a left-side view thereof;

FIG. 6 is a bottom view thereof; and,

FIG. 7 is a top view thereof.

The broken lines in the drawings depict environmental matter and form no part of the claimed design.

1 Claim, 7 Drawing Sheets
